UNITED STATES PATENT OFFICE

PAUL E. ALLEN, OF NILES CENTER, ILLINOIS

BOTTLE HOLDER

Application filed February 6, 1928. Serial No. 252,140.

This invention relates to improvements in bottle holders and more particularly to the type of bottle holder adapted for use by babies which may be conveniently placed in position for use by a baby when lying down or in a sitting or inclined position and which may be conveniently adjusted for use.

Among the objects of my invention are to provide a gripping device for the bottle which 10 may be readily manipulated to apply the bottle thereto, or to remove the same, and which will securely hold the bottle; further to provide a novel construction of bottle holder having a base of sufficient weight to give it stability and adapted to lay in the crib or buggy and the base thereof adapted to readily adjust 15 itself to the surface or object on which it is placed; further to provide a new and novel construction of base for such bottle holder enabling a material of sufficient weight, the 20 filler for said base comprising a yieldable material; further to provide a new and novel base having means for securing access to the interior of said base in order to change, removing or refill the base with the yieldable 25 material; further to provide a gripping means for the bottle of new and novel construction adapted to firmly hold the bottle in the adjusted position; further to provide a bottle 30 holder of maximum simplicity, efficiency, economy and ease of operation; and such further objects, advantages and capabilities as will later more fully appear.

My invention further resides in the combination, construction and arrangement of parts illustrated in the accompanying drawings, and while I have shown therein a preferred embodiment, I desire it to be understood that the same is susceptible of modification and change without departing from the spirit of my invention.

In the drawings:

Fig. 1 is a view in side elevation of my new and novel bottle holder having a bottle inserted in the gripping means, the bottle holder and bottle being also shown in dotted outline in an adjusted position.

Fig. 2 is a top plan view of my construction.

Fig. 3 is a vertical cross sectional view on the line 3—3 of Fig. 2.

Fig. 4 is a fragmentary view in side elevation of my bottle holder, but disclosing an alternating form of holding or gripping means.

Fig. 5 is a vertical cross-sectional view on the line 5—5 of Fig. 4.

Fig. 6 is a top plan view of the bottle holder showing the bottle removed, the holder being provided with an alternate form of holding or gripping means.

Fig. 7 is a vertical cross-sectional view on the line 7—7 of Fig. 6 and disclosing means providing access to the interior of the base.

Fig. 8 is a top plan view with an alternate form of holding or gripping means for the bottle, a fragmentary portion of the bottle being shown in dotted outline.

Fig. 9 is a view in perspective of the holding or gripping means shown in Fig. 8.

Referring to the drawings, the bottle holder comprises a base 1 and a holding or gripping means for holding or gripping a bottle. In Figs. 1, 2 and 3, the holding or gripping means comprises a pair of elastic bands 2, 2. Although two members are shown in the drawings, any number of bands or a single member may be provided, the only requisite being that this member be of sufficient width to hold the bottle in its adjusted position and prevent its easy displacement. This gripping or holding means is attached to the base 1 by any suitable means. The body or base 1 comprises a bag of rubber or of any yieldable fabric, which will readily adapt itself to the configuration of the body or material upon which this base or body is placed. It readily adjusts itself so that the bottle may be placed in any angle depending upon the position of the baby. The bottle is designated generally at 3 and is provided with a nipple 4 of the usual construction. The material that is used as filler in the base or body is generally sand, gravel, shot, or other suitable yieldable material of desirable weight, so that when the body is placed upon an object it will readily adapt itself to the configuration of the object on which it is placed, and at the same time the material or filler in the body will adjust itself as shown more clearly

100

in Fig. 1 of the drawings. The holding members 2, 2 are of elastic or other suitable yieldable material which may be stretched when the bottle is to be inserted and thereafter to contract and tightly grip the bottle and hold it in position.

In Figs. 4 and 5, the holding means is shown as a single web or strip 2^a of elastic or other suitable yieldable material, this holding means being provided with a pair of fasteners 5, 5. The portion of the holding means adjacent the base or body 1, is secured thereto by any suitable means providing a substantially rigid connection between the holding means and the body or base. Being of elastic or yieldable material, the holding means 2^a will readily adapt itself to bottles of different diameters or cross sections.

In Figs. 6 and 7 are disclosed an alternate form of base or body 1^a provided with a metallic holding means 2^b. The holding means comprises a pair of resilient fingers 6, 6 provided at the lower surface with a screw cap member 7, adapted to screw into the top of the body or base. These resilient fingers are suitably connected to the screw cap member, or they may be made integral therewith so as to provide a rigid connection with the screw cap member which in turn is connected to the body or base. This screw cap member allows access to the interior of the body or base for changing, removing, or refilling the contents of the body or base. A second screw cap 8 may be provided in the bottom of the base or body. This allows ready access to the bottom for the filling or refilling of the contents without removing the holding means and the upper cap member. Although Fig. 7 shows a screw cap member in both the top and bottom, only one such member is necessary to secure access to the interior of the body or base. Although a screw cap means is disclosed, a friction cap or lid means such as is ordinarily used in cans or containers where the cap or lid is secured to the can or container by friction alone, may be provided.

Figs. 8 and 9 disclose an alternate construction of holding means or keeper comprising a metallic member having an arcuate extension 9 provided with fingers 10, 10 of suitable yieldable material. These fingers may be made integral with the extension or may be attached thereto by any suitable means so as to provide a substantially rigid construction. The extension 9 slides into a keeper 11 attached to the body or base of the holder. When it is desired to insert a bottle into the holding means, the resilient fingers 10, 10 are forced apart and the bottle is inserted therein and fit conformably in the extension 9. The keeper prevents displacement of the bottle and the fingers and extension hold the bottle in adjusted position.

In the construction disclosed, the body is of some yieldable material or fabric that read-

ily adjusts itself to the position in which it is placed and to the configuration of the body or materials upon or against which it contacts. The holder is admirably adapted for being positioned in the bed, go-cart, carriage, or other container or vehicle in which the baby is placed, the base of the holder being of sufficient weight and filled with suitable yieldable material so that the position in which the holder is placed cannot be readily altered by the baby. It prevents the ready displacement of the bottle so that when the same is positioned at a certain height or angle, it will remain at such height and angle so that the baby may, without undue exertion, avail itself of the contents of the bottle. My construction does away with the use of projecting fingers or pedestals having projecting fingers that are dangerous to a baby. There are no sharp projections with which the baby's head or body may contact so that there is no danger of injury accompanying the use of my improved bottle holder. In the construction shown in Figs. 1 to 3 inclusive, the bottle holder is constructed entirely of rubber or other fabric except for the filler which is contained in the base, so that it can be washed or cleaned and thus kept in sanitary condition. Also it is perfectly harmless to the baby as no metallic members or projections are provided with which the baby could contact. In this form, the filler is inserted before the bag or base is closed or sealed, and access to the interior thereafter, is not necessary. It will be particularly observed that in all of the forms of the invention above described, the holding means has a normally fixed or immovable engagement with the base, so as to prevent any substantial movement of the bottle with respect to the base, while in use.

Having thus disclosed my invention, I claim:

1. A bottle holder comprising a bag of flexible material, a filler for said bag which is yieldable so that said bag will adapt itself to the configuration of any support upon which it may rest, and bottle holding means located wholly outside of the base so as to support the bottle exteriorly of the latter, said holding means having a normally immovable engagement with said base, so as to prevent any substantial movement of the bottle relative to the base.

2. A bottle holder comprising a bag of flexible material, a filler of heavy mobile particles adapted to change their position, so that said bag will adapt itself to the configuration of any support upon which it may be placed, and bottle holding means positioned to support a bottle entirely outside of the bag.

3. A bottle holder comprising a bag of flexible material, a filler of heavy mobile particles within said bag capable of changing their relative positions, and resilient bottle engaging means connected with said bag exterior-

ly thereof and constituting the sole bottle engaging means, said bottle engaging means having a normally immovable engagement with said base, so as to prevent any substantial movement of the bottle relative to the base.

4. A bottle holder comprising a flexible bag having a filler of heavy mobile particles capable of changing their relative positions, and a bottle engaging clip connected with the exterior of said bag and positioned to support a bottle above the same.

5. A bottle holder comprising a flexible bag provided with a yieldable filling material, said bag being provided with an opening for access to the interior thereof, means normally closing said opening, and means for holding a bottle in a position above and resting upon said bag.

20 6. A bottle holder comprising a flexible bag provided with a yieldable filling material, said bag being provided with an opening for access to the interior thereof, means normally closing said opening, said closing means being provided with a bottle engaging clip.

25 In witness whereof, I hereunto subscribe my name to this specification.

PAUL E. ALLEN.
